UNITED STATES PATENT OFFICE

EMILIO CRESPI, OF CRESPI-SUR-L'ADDA, ITALY, AND MARIUS PAUL OTTO, OF PARIS,
FRANCEAPPARATUS FOR BLEACHING TEXTILE FIBERS WITH A GASEOUS CURRENT, SUCH AS
OZONIZED AIROriginal application filed November 30, 1926, Serial No. 151,785, and in France February 2, 1928. Divided
and this application filed June 21, 1929. Serial No. 372,700.

The object of the present invention is to provide improved means and apparatus for exposing textiles to gaseous bleaching currents, for example, to currents of ozonized air, for obtaining a uniform distribution of the gaseous current over the whole of the material to be bleached for providing for a continuous and practical operation, and, at the same time, utilizing all the gas supplied and paying due regard to the health of the workmen engaged in this work.

An arrangement according to the preferred form of the invention is shown in the accompanying drawings, wherein:—

15 Fig. 1 is a longitudinal axial section of an apparatus according to the invention for the treatment of pieces of textile;

20 Fig. 2 is partly an elevation and partly a longitudinal vertical section of the chamber for the treatment of the textile pieces;

25 Fig. 3 is a part plan and part horizontal section of this chamber; and

Fig. 4 is a transverse vertical section of the chamber.

30 This machine comprises an autoclave 194 in which the pieces or strip of textile 195 is boiled, at an approximate pressure of three atmospheres, for about seven hours. The boiling liquid is preferably a solution made with six per cent melted caustic soda and one per cent of sodium sulfocinicate. On leaving the autoclave the pieces of textile pass through an opening mechanism 196 and then to a folding means 197, by which the 35 material is folded into a deposit 198'. The material then passes into a vessel 200 providing an acid bath, then into a vessel 201 where it is washed with water, and then into an ozonizing chamber 202, whence it passes into another folding device 197 after which a deposit 198² of folded material is formed. The bleached textiles then pass into a vessel 203 where soaping and washing is effected, then to a drying apparatus 204, and finally 40 to another folding means 197, the material 45 finally being formed as a deposit 198³.

The ozone necessary for the bleaching operation is produced by an ozonizer 207 supplied by a fan 208 with air dried in the 50 desiccator 209; the ozonized air being meas-

ured in meter 206 and conveyed through pipe 205 into the ozonizing chamber 202. This ozonizing chamber has various characteristic features described hereinbelow.

In the first place an improved process for bleaching textiles is utilized in this chamber, the process being characterized in that the gaseous ozonized mixture acts on the pieces of textile, suspended in such a way as to form adjacent folds, and penetrates between the folds to effect bleaching of the material.

The invention also comprises an ozonizing chamber for the application of this improved process or of other similar process and characterized by double sides forming a free space into which the gaseous ozonized mixture is admitted and from which the mixture rushes into the interior of the chamber, wherein the pieces of textile are suspended and bleached.

70 The ozonizing chamber (Figs. 2 to 4) consists of a chamber 101 of considerable length having two brick walls 102 and 103 forming a double wall and leaving a free space 104 between them. The inner wall 103, constructed, for example, of enamel bricks, is provided with openings 105 by which the free space 104 is brought into communication with the inner bleaching chamber. There are two partitions 106' 106² dividing the free space 75 104 into two separate parts 104' 104² to which are connected the two conduits 117' and 117² for the supply of ozonized air. These two conduits are identical; each of them comprises an intake pipe 110' 110² connected to 80 the ozone generator and provided with a control valve 111' 111², and also an exit pipe 112' 112² provided with valve 113' 113². A distributing pipe 115' 115² with nozzles 116' 116² is connected between the intake pipe 110' 85 110² and the exit pipe 112' 112². These nozzles 116' 116² lead to the free spaces 104' 104².

90 The piece of textile 118 for treatment is placed on rods 119 fitted in the upper part of the chamber 101; these rods are very close together so that the piece of textile will be in form of numerous folds close together, as 95 shown in Fig. 2.

The apparatus described is operated as follows:—

The valves 111' and 113² are opened, the valves 113' and 111² remaining shut; the ozonized mixture comes from the ozone generator through members 110', 115' and 116' and penetrates into the part 104² of the space 104. This gaseous mixture passes through the openings 105 provided between the bricks 10 of wall 103, penetrating into the inner treatment chamber and easily filtering between the folds of the textile sheet 118, and this produces regular bleaching of the piece. Finally, the gaseous mixture, when deprived of 15 the greater part of its ozone, makes its escape through the orifices 105 in the part 104² of the space 104, the nozzles 116², the pipe 115², the cock 113² and the pipe 112². The arrows 125 of Fig. 3 show the direction of this circulation.

It will be seen that the nozzles 116' 116², being regularly distributed in the vertical wall 102, as shown in Fig. 2, and the orifices 105, being themselves regularly arranged in 25 all the surface of this wall, a very regular distribution of the gaseous ozonized mixture is produced inside the treatment chamber and consequently over all the surface of the piece of textile 118. This piece is thus bleached in 30 a perfectly regular way.

The direction of flow of the gaseous ozonized mixture in the apparatus can be changed, by shutting valves 111' 113² and opening valves 111² 113¹; the gaseous ozonized mixture then flows through the plant in a direction opposite to arrows 125 in the way already described in detail.

Numerous alterations can be made in the aforesaid plant, which is given as an example. In particular, the inner wall 103 and the spaces 104' 104² can be omitted, the nozzles 116' 116² opening directly into the inner chamber where the piece of textile 118 is suspended. By this means the construction of the plant is simplified, but such a perfect distribution of the ozonized mixture cannot then be obtained.

The invention evidently comprises the aforesaid appliances whatever gaseous mixture may be used for bleaching the textiles.

What we claim as our invention, and desire to secure by Letters Patent is:—

1. In an apparatus for bleaching textiles by a gaseous mixture, such as ozonized air, the combination of a double walled chamber with a free space between said double walls, means in said chamber for supporting the piece of textile to be treated, partitions dividing the free space into two parts, means providing communication between said free space and said chamber, pipes for conveying the gaseous mixture into one of the parts of the free space, and pipes for discharging the gaseous mixture from the second part of said free space whereby the gaseous mixture passes

through the chamber and acts on the piece of textile.

2. In an apparatus for bleaching textiles with a gaseous mixture, such as ozonized air, the combination of a double walled chamber having a free space between said double walls, means in said chamber for supporting the piece of textile to be treated, partitions dividing the free space into two parts, means providing communication between said free space and said chamber, piping communicating with the two parts of said free space and valves fitted on said piping to reverse the direction of flow of the gaseous mixture through the said chamber.

In testimony whereof we affix our signatures.

EMILIO CRESPI.
MARIUS PAUL OTTO.
